J. M. LOUGHLIN.
ELECTRICALLY ILLUMINATED SIGN.
APPLICATION FILED MAY 4, 1912.

1,064,506.

Patented June 10, 1913.

UNITED STATES PATENT OFFICE.

JAMES M. LOUGHLIN, OF CHICAGO, ILLINOIS, ASSIGNOR TO THOMAS CUSACK COMPANY, A CORPORATION OF NEW JERSEY.

ELECTRICALLY-ILLUMINATED SIGN.

1,064,506.

Specification of Letters Patent. Patented June 10, 1913.

Application filed May 4, 1912. Serial No. 695,041.

To all whom it may concern:

Be it known that I, JAMES M. LOUGHLIN, a citizen of the United States, and a resident of Chicago, in the county of Cook and 5 State of Illinois, have invented certain new and useful Improvements in Electrically-Illuminated Signs; and I do hereby declare that the following is a full, clear, and exact description thereof, reference being 10 had to the accompanying drawings, and to the letters of reference marked thereon, which form a part of this specification.

This invention relates to improvements in electrically illuminated signs and consists 15 of the matters hereinafter described and more particularly pointed out in the appended claims.

In the drawings:—Figure 1 is a view showing my improved sign in side elevation. Fig. 2 is a view representing an end elevation of the same. Fig. 3 is a view representing a partial vertical section through the sign in a plane indicated by the line 3—3 of Fig. 1. Fig. 4 is a view 25 representing a partial horizontal section through the sign in a plane indicated by the line 4—4 of Fig. 1. Fig. 5 is a fragmentary side elevation of the sign showing a modified form of the construction. Fig. 6 30 is a view representing a horizontal section through Fig. 5, in a plane indicated by the line 6—6 thereof.

The object of my invention is to provide a sign of economical construction comprising, together with electrical illuminating means, one or more fixed transparent or translucent sign panels adapted to be illuminated by transmitted light from said electrically illuminating means, and a removable 35 panel adapted to be illuminated by reflection from the same source and to be easily replaced by a like panel on which is depicted other or different advertising matter.

Referring now to that embodiment of my invention illustrated in Figs. 1 to 4, inclusive, the same is made of sheet metal and consists of an inclosed box 10 having oppositely inclined, downwardly converging, side walls 11, 11, connected together at 50 their lower edges, a top wall 12 and end walls 13, 13, which project beyond the cross-sectional limits of the box proper and provide supports for horizontally spaced, fixed sign panels 14, 14, located on the level of

the box 10 and at either side thereof, and of a removable sign panel 15 located below the box 10 and in a plane intermediate the planes of the first named panels 14. The inclined side walls 11, 11, of the box provide supports for sockets 17 of a plurality of lamps 16, 16, arranged in horizontal lines in each of said walls. Each row of said lamps, by reason of the inclination of the side walls and by reason of its location back 60 of the panels 14, 14 and above and at each side of the panel 15, is adapted to illuminate one of the panels 14 and one face of the panel 15, the panel 14 by light rays transmitted through it and the panel 15 70 by light rays thrown directly upon its face.

The sockets 17 of the lamps 16 are attached to the walls 11, 11, of the box 10, in any convenient and familiar manner, so that their terminals and the wires connected 75 to them (not shown), are located entirely within the box 10 and are protected from rain, snow and other forms of precipitated moisture. The top wall 12 of the box 10 is higher at its longitudinal median line 80 than each lateral edge and as shown is curved so that any water which collects on the top wall will be shed therefrom.

The inclined side walls 11, 11 are made in one piece which is bent upon itself to form 85 laterally spaced, longitudinally extending, depending flanges or ribs 11^a, 11^a, where the two sides 11, 11, meet. Said flanges provide a groove in which the upper longitudinal margin of the sign panel 15 is adapted 90 to be engaged. At the ends of the side walls 11, 11, are provided flanges 11^b located in vertical planes. The end walls 13, 13 of the box 10 are soldered to said flanges 11^a and to the end edges of the top wall 10. 95 Outwardly extending lateral flanges 11^c, 11^c are provided at the upper longitudinal edges of the side walls 11, 11, and the top wall 12 is turned over and under said outwardly extending flanges 11^c, as plainly indicated 100 in Fig. 3. The box 10 is thus made moisture proof.

Each of the end walls 13, 13 is bent upon itself adjacent to its vertical median line to form a vertically extending flange 18 projecting from its inner face. In each edge of the vertical end margin of the panel 15 are provided vertically extending spaced flanges 19, 19, forming a deep groove adapted 105 to receive one of the vertical flanges or 110

ribs 18, 18 of the end walls 13 of the box 10. Said panel 15 is supported in place by means of bolts 20 which extend through suitable apertures formed in the flanges 18, 18 of said end walls and the flanges 19, 19 at each end of the panel 15. Thus to attach the panel 15 to the sign, said panel is pushed upwardly from below with the vertical ribs or flanges 18 on the end walls 13 of the sign engaged within the grooves formed by the flanges 19, 19, at each end of the said panel, until the upper margin of the panel is brought into engagement within the downwardly opening groove formed by the flanges 11^a, 11^a at the lower longitudinal edge of the box 10. The bolts 20 are then inserted through the apertures provided, respectively, in the flanges 19 and in the flanges 18.

20 A number of panels 15 each containing different advertising matter may be provided for each sign and the said panels may be interchanged as desired. On the fixed panels will be placed matter which does not have to be changed, as a general name giving the character of the particular business carried. As shown in the drawings, the fixed panels carry the words "drugs," while the removable panel is used to advertise a certain cigar. This may be replaced from time to time by panels advertising other cigars or other goods.

The fixed panels 14 may be of any familiar construction and as shown consist of a metallic frame 14^a attached at its ends to the end walls 13 of the sign box and contain a transparent or translucent plate, upon which is depicted the advertising matter.

The sign is supported, as shown in the drawings, on a horizontal rod 25 projecting from a suitable support, as the wall of a house. Bars 26, 26 are secured by rivets or in any other convenient manner to the outer faces of the end walls of the box 10 and are projected above the level of the sign where they are provided with hooks 26^a, 26^a adapted for engagement upon the rod 25.

Instead of the single rib or flange 18 on the end walls of the sign box, and the associated pairs of spaced flanges on the ends of the removable panel 15, these parts may be reversed and the single rib be provided on the sign tablet, and the pairs of spaced flanges provided on the said end walls. Such a modification is illustrated in Figs. 5 and 6. In this case, 27 indicates the end walls of the box, which, as shown in the drawings, are made flat throughout. 28 indicates vertically extending channel mem-

bers attached to the inner faces of said end walls below the level of the box 10. Said channel members, as shown, are each formed by bending a piece of thin metal upon itself

to provide spaced flanges 28^a. The end margins of the panel 29 constitute projecting flanges and are adapted to engage in the grooves formed by said flanges 28^a, and the marginal end parts of the panel and the flanges 28^a are provided with suitable apertures to receive bolts 30. Otherwise the construction is the same as that heretofore described.

I claim as my invention:—

1. In an illuminated sign, in combination, a longitudinally extending supporting member having oppositely inclined, downwardly converging sides adapted for the attachment of illuminating devices, end members which project laterally beyond said main supporting member and vertically below the same, fixed translucent panels in horizontal alignment with the inclined sides of said supporting member, and a removable sign panel located intermediate of and below said inclined sides, said end members and the ends of said removable sign panel being each provided, the one with a pair of spaced flanges to form a groove, and the other with a single flange adapted for engagement in said groove, the said associated flanges being provided with apertures to receive supporting bolts.

2. In an electrically illuminated sign, in combination, a closed box extending longitudinally of the sign, said box having oppositely inclined, downwardly converging side walls adapted for the attachment of electric lamp sockets, and end walls which project laterally beyond said side walls and vertically below the same, means forming laterally spaced, longitudinal flanges at the lower edges of said side walls providing a downwardly opening groove, fixed translucent sign panels in horizontal alignment with the inclined sides of said box having their ends attached to the said end walls, and a removable sign panel located intermediate of and below said inclined side walls and having a part along its upper longitudinal edge adapted to engage within said downwardly opening groove, said end walls and the ends of said removable sign panel being each provided, the one with a pair of spaced flanges to form a groove and the other with a single flange adapted for engagement in said groove, the said flanges being provided with associated apertures to receive supporting bolts.

In testimony, that I claim the foregoing as my invention I affix my signature in the presence of two witnesses, this 17th day of April A. D. 1912.

JAMES M. LOUGHLIN.
